UNITED STATES PATENT OFFICE

2,388,426

SOLE ATTACHING PRESS

Kenneth W. Macdonald, Winchester, Mass., assignor to Compo Shoe Machinery Corporation, Boston, Mass., a corporation of Delaware

Application January 20, 1944, Serial No. 518,938

9 Claims. (Cl. 12—33)

This invention relates to presses for attaching soles to shoes and relates more particularly to presses having dilatable diaphragms for pressing soles against shoe uppers.

As is known, in the cementing of soles to shoe uppers, it is customary to press the soles against the shoe uppers by dilatable diaphragms which act against the bottoms of the soles. Prior presses of this type have not been entirely satisfactory for the reason that the diaphragms expand or balloon excessively outside the contour of the shoe bottom thus rolling the edge of the sole upward which is undesirable, especially around the forepart and heel portions of extension edge shoes of the welted type. Only at the inside shank portion of the shoe it is desirable to wrap or curl the sole and welt upward against the shoe upper.

A feature of this invention resides in the provision of diaphragm restraining members so shaped that the dilation of the sole pressing diaphragm is restrained more at the heel and forepart of a shoe than at the shank whereby the dilation of the diaphragm corresponds to the contour of the shoe bottom.

Welt holdowns are primarily used for applying pressure to the welt or sole extensions of a shoe and in some cases they are relied on to prevent curling of the sole extension, by using an excessive pressure to react against the sole pressure applying medium. Such prior holdowns have been complicated in structure and have required elaborate positioning and adjusting mechanisms. Furthermore these prior devices damage the welt and/or sole extension as they are not capable of distributing the applied pressure uniformly.

Another feature of this invention resides in the provision of an inflatable bag as a welt holdown which applies pressure uniformly to the welt or sole extension.

Other features of this invention reside in the provision of a pivoted box enclosing an inflatable welt holdown bag, and in the provision of a pivoted, ratchet adjusted, heel post having a yielding last engaging plate, the box and the heel post being adapted to be swung down and latched following the insertion of a shoe into the press and prior to the dilation of the sole pressing diaphragm and the inflation of the welt holdown bag.

An object of the invention is to restrain the dilation of a sole pressing diaphragm more at the heel and forepart of a shoe than at the shank.

Another object of the invention is to apply

any desired uniform pressure to a welt or sole extension of a shoe by an inflatable pressing bag.

Other objects of the invention are to simplify, and to improve the performance of, shoe presses having dilatable sole pressing diaphragms and welt holdowns.

The invention will now be described with reference to the drawings, of which:

Fig. 1 is a side elevation partially in section, of a shoe press embodying this invention;

Fig. 2 is a sectional plan view taken along the lines 2—2 of Fig. 1;

Fig. 3 is a sectional view taken along the lines 3—3 of Fig. 2;

Fig. 4 is a sectional view taken along the lines 4—4 of Fig. 1;

Fig. 5 is a section similar to Fig. 4 except that the sole pressure diaphragm is shown dilated and the welt holdown bag is shown inflated, and

Fig. 6 is a sectional view taken along the lines 6—6 of Fig. 1.

Referring to the drawings and first to Figs. 1, 2 and 4 thereof, there is shown a shoe press having a base frame casting 10 having the vertical extensions 11 which have the extended substantially horizontal surfaces 12 upon which the marginal edges of the diaphragm 13 are supported. The diaphragm 13, the extensions 11 and the lower wall of the base 10 form a diaphragm chamber 14 into which air may be injected through the valve 15 for dilating the diaphragm as will be described.

The upper base casting 16 has the lower horizontal extension 17 resting upon the upper marginal surfaces of the diaphragm 13 and has the upper horizontal surface 18 upon which the lower surfaces of the welt holdown bag retaining box 19 rest, as illustrated by Figs. 1 and 4, when the shoe to be cemented has been inserted ready for the sole and welt pressing operations.

The resilient welt holdown bag 20 is contained within the retaining box 19 and is adapted to be inflated by air applied through the valve 21 and the fitting 22 as will be described. The wall of the bag 20 has varying thickness and is so shaped that when the bag is inflated, the thinnest portion will expand down and towards the welt crease of a shoe held in the press, first, thus preventing the possibility of the air bag being forced between the sole and the welt. The bag may be constructed of rubber or equivalent material which cannot damage the finish of a shoe so that speedy positioning of a shoe is assured.

The box 19 is hinged at 23 about the pin 24 and is adapted prior to the insertion of a shoe in

the press, to be swung upwardly as illustrated generally by the dashed lines of Fig. 1. The spring 25 has its lower end attached to the screw 26 which is threaded into the upper surface of the box 19, and has its upper end attached to the screw 27 which is threaded into the yoke 28. The spring 25 serves to retract the box 19 to its upward position when a latch to be described is released.

The band 30 is attached by the bolts 31 to the opposite sides of the base 10 and extends over and above the base 10, and supports by the bolts 32, the heel and toe post yoke 28.

The yoke 28 is drilled to receive the toe post adjusting shaft 33 which is threaded at its lower end into the toe post 34. The toe plate 35 is attached to the post 34 and the toe rubber 36 is attached to the underside of the plate 35. The hand wheel 37 serves to rotate the shaft 33 and to raise and lower the toe post 34 and the toe rubber 36 which contacts the toe of a shoe in the press. The toe post thus may be adjusted to obtain the degree of dilation of the diaphragm 13 which is desired. For example, less diaphragm dilation would be desired on a flat bottom last than on a rocker bottom last.

The heel post supporting member 40 is attached to the yoke 28 by the bolts 41 and 42 and the two similar heel post supporting arms 44 are each pivotally attached at one end thereof to the member 40 about the bolt 45 and at the other end thereof are each pivotally attached to the heel post support 46 about the bolt 47. The heel post plate 48 is yieldingly attached to the heel post support 46 by the screws 49 which are threaded into the heel post plate 48 and which are freely slideable in aligned openings drilled in the base of the support 45. The spring 50 extends between the heel post plate 48 and the support 46 in recesses therein and while forcing the support 46 and the heel post plate 48 apart, yields under the pressure of the last 51 when the diaphragm 13 is fully dilated as will be described.

The ratchet 52 is formed on the outer end of the heel post supporting member 40, and the pawl 53 which is pivoted on the pin 54 to the arms 44, engages the ratchet 52 when the heel post plate 48 is against the last 51 as illustrated by Fig. 1. The member 55 attached to the pin 54 is adapted to be depressed manually for releasing the pawl from the ratchet when the pressing operations are concluded. The springs 56 are secured to and extend between the pawl 53 and the arms 44 and serve to urge the pawl towards ratchet engaging position. The springs 57 are secured to and extend between the arms 44 and the member 40 and serve to lift the arms 44 and the heel post assembly to the position indicated by the dashed lines of Fig. 1 when the pawl 53 is released.

The lock latches 60 are pivoted about the pins 61 which are journaled in the upper base casting 16 and are adapted to engage the lock pins 62, which are attached to opposite sides of the air bag retaining box 19, when the box 19 is in shoe engaging position as illustrated by Fig. 1. The lock latches 60 are adapted to be manually or otherwise disengaged from the lock pins 62, by clock-wise rotation thereof (with reference to Fig. 1 of the drawings) and when they are disengaged, the spring 25 swings the box 19 upwardly about the pivot pin 24 to the position indicated by the dashed lines of Fig. 1.

As illustrated best by Figs. 5 and 6, the upper base casting 16 forms a restraining cover for the

diaphragm 13, its under surfaces being so shaped that the dilation of the diaphragm 13 is restrained more in the heel and fore-part portions than in the shank portion of a shoe positioned in the press. With reference to Fig. 5, the lower walls 65 of the upper base casting 16 limit the upper movement of the diaphragm 13. The walls 65 continue uniformly in the heel and toe portions of the press but in the shank portion are replaced as illustrated by Fig. 6, by the wall 66 on one side and the wall 67 on the other side which permit greater upper movement of the diaphragm 13, which greater movement results in the sole being curved more and pressed more tightly at the shank than in other portions of the shoe whereby the sole conforms more accurately to the contour of the shoe bottom.

At the start of a shoe pressing operation, the heel post plate 48 and the welt holdown bag retaining box 19 will be swung upwardly as illustrated by the dashed lines of Fig. 1. The welt holdown bag 20 and the diaphragm chamber 14 will be deflated. The toe post 34 will have been adjusted by movement of the hand wheel 37 so that the toe rubber 36 is in the proper position for the particular shoe to be worked upon.

The operator then places a shoe in the press and pulls down the heel post assembly so that the plate 48 rests against the heel portion of the last 51 whereupon the pawl 53 engages the ratchet 52 maintaining the heel post in position. The welt holdown retaining box 19 is then swung down and the lock latches 60 positioned over the lock pins 62 for locking the box in position. Air is then admitted through the valve fitting 15 into the diaphragm chamber 14, and the diaphragm 13 is dilated and applies pressure to the underside of the sole of the shoe as illustrated by Fig. 1, and raises the shoe upwardly a distance determined by the positions of the heel and toe posts which distance may, for example, be one-half an inch. The spring 50 permits the heel post plate 48 to yield that distance.

The operator then admits air through the valve fitting 21 into the welt holdown bag 20 which, upon inflation, first expands over the shoe into the welt crease, and then applies downward pressure against the welt as illustrated by Figs. 5 and 6.

Although separate inflation valve fittings have been illustrated for separately inflating the diaphragm chamber and the welt holdown bag, the welt holdown bag may be connected to the diaphragm chamber through a reducing valve and the inflation of both chambers and bag may be accomplished through a single valve fitting as disclosed in the Fred Dawson Patent No. 2,348,060.

While one embodiment of the invention has been described for the purpose of illustration, it should be understood that the invention is not limited to the exact apparatus and arrangement of apparatus illustrated as modifications thereof may be suggested by those skilled in the art without departure from the essence of the invention.

Having described my invention, what I claim as new and desire to secure by Letters Patent, is:

1. In a shoe press having a member for engaging the toe of a lasted shoe, an arcuate welt holdown retaining member having a horizontal flange extending around and spaced from said toe engaging member, and an arcuate inflatable welt holdown bag held by said retaining member and limited in its movement thereby.

2. In a shoe press having a sole pressing pad and a member for engaging the toe of a lasted

shoe, an arcuate welt holdown retaining member having a horizontal flange extending around and spaced from said toe engaging member, an arcuate inflatable welt holdown bag held by said retaining member and limited in its movement thereby, and means pivoting said retaining member to said press for swinging movement towards and away from said sole pressing pad.

3. In a shoe press having a sole pressing pad and a member for engaging the toe of a lasted shoe, an arcuate welt holdown retaining member having a horizontal flange extending around and spaced from said toe engaging member, an arcuate inflatable welt holdown bag secured to the flange of said retaining member, and means pivoting said retaining member at its toe end to said press for swinging movement towards and away from said sole pressing pad.

4. In a shoe press having a member for engaging the toe of a lasted shoe, an arcuate welt holdown retaining box extending around and spaced from said member, an arcuate inflatable welt holdown bag in said box, an inflatable sole pressing diaphragm, and means forming a passage between said bag and said diaphragm into which passage said bag expands and contacts said diaphragm when said bag and diaphragm are inflated.

5. A shoe press comprising an arcuate inflatable welt holdown bag, an inflatable sole pressing diaphragm, and means forming a passage between said bag and said diaphragm into which passage said bag expands and contacts said diaphragm when said bag and diaphragm are inflated.

6. In a shoe press having a member for engaging the toe of a lasted shoe and a member for engaging the heel of the shoe, an arcuate inflatable welt holdown bag around and spaced from said toe engaging member, one end of said bag extending adjacent said heel engaging member on one side of said press and the other end of said bag terminating substantially short of said heel engaging member on the other side of said press, an inflatable sole pressing diaphragm, and diaphragm retaining walls for limiting the movement of said diaphragm when same is inflated, towards said bag, one of said walls opposite said one end of said bag being arranged to permit said diaphragm to move further towards said bag than permitted by the other of said walls.

7. In a shoe press having a member for engaging the toe of a lasted shoe and a member for engaging the heel of the shoe, an arcuate inflatable welt holdown bag around and spaced from said toe engaging member, one end of said bag extending adjacent said heel engaging member on one side of said press and the other end of said bag terminating substantially short of said heel engaging member on the other side of said press, an inflatable sole pressing diaphragm, retaining walls for limiting the movement of said diaphragm when same is inflated, towards said bag, one of said walls opposite said one end of said bag being arranged to permit said diaphragm to move further towards said bag than permitted by the other of said walls, and means forming a passage between said bag and said diaphragm into which passage said bag expands and contacts said diaphragm when said bag and diaphragm are inflated.

8. In a shoe press having a member for engaging the toe of a lasted shoe, an arcuate welt holdown retaining box extending around and spaced from said member, an arcuate inflatable welt holdown bag in said box, means pivoting said box at its toe end to said press, an inflatable sole pressing diaphragm, and means forming a passage between said bag and said diaphragm into which passage said bag expands and contacts said diaphragm when said bag and diaphragm are inflated.

9. In a shoe press having a member for engaging the toe of a lasted shoe and a member for engaging the heel of the shoe, an arcuate welt holdown retaining box around and spaced from said toe engaging member, means pivoting said box at its toe end to said press, one end of said box extending adjacent said heel engaging member on one side of said press and the other end of said box terminating substantially short of said heel engaging member on the other side of said press, an arcuate inflatable welt holdown bag in said box, an inflatable sole pressing diaphragm, and diaphragm retaining walls for limiting the movement of said diaphragm when inflated, towards said bag, one of said walls opposite said one end of said box being arranged to permit said diaphragm to move further towards said bag than permitted by the other of said walls.

KENNETH W. MACDONALD.
